Primary Examiner — Wan Laymon*Assistant Examiner* — Clint A Samuel(74) *Attorney, Agent, or Firm* — McGarry Bair PC**CLAIM**

The ornamental design for a ceiling fan light cage, as shown and described.

DESCRIPTION

FIG. 1 is a bottom perspective view of a ceiling fan light cage in the environment of a ceiling fan, showing my new design;

FIG. 2 is a top perspective view of the ceiling fan light cage without the ceiling fan environment;

FIG. 3 is a top view thereof;

FIG. 4 is a bottom view thereof;

FIG. 5 is a right side view thereof;

FIG. 6 is a left side view thereof;

FIG. 7 is a front view thereof; and,

FIG. 8 is a rear view thereof.

Portions of the ceiling fan light cage and the ceiling fan environment are shown in broken lines, which form no part of the claimed design.

1 Claim, 8 Drawing Sheets(56)
